(57) **CLAIM**

The ornamental design for a spinal implant, as shown and described.

DESCRIPTION

FIG. 1 is a perspective view of an exemplary spinal implant; FIG. 2 is a top view of an exemplary spinal implant; FIG. 3 is a bottom view of an exemplary spinal implant; FIG. 4 is a side view of an exemplary spinal implant; FIG. 5 is a side view of an exemplary spinal implant; FIG. 6 is a front view of an exemplary spinal implant; and, FIG. 7 is a back view of an exemplary spinal implant. The broken lines illustrate portions of the spinal implant and form no part of the claimed design.
